UNITED STATES PATENT OFFICE.

ELMER O. BEARDSLEY, OF CHICAGO, AND WALTER F. PIPER, OF OAK PARK, ILLINOIS,
ASSIGNORS TO THE BEARDSLEY & PIPER COMPANY, OF CHICAGO, ILLINOIS, A COR-
PORATION OF ILLINOIS.

MOLDING MACHINE.

1,408,493.

Specification of Letters Patent. Patented Mar. 7, 1922.

Application filed March 14, 1921. Serial No. 452,063.

To all whom it may concern:

Be it known that we, ELMER O. BEARDSLEY and WALTER F. PIPER, both citizens of the United States, and residents of Chicago, in the county of Cook and State of Illinois, and Oak Park, in the county of Cook and State of Illinois, respectively, have invented certain new and useful Improvements in Molding Machines, of which the following is a full, clear, and exact description.

The invention relates to molding machines and more particularly to those of the projector type.

The objects of the invention are: to provide an improved mount for the rotor of a sand projector to lessen the vibration resulting from high speed rotation incident to sand projection; to provide improved means for operating a vibratory sand conveyor and riddle by which vibration of the support on which the conveyor is movably mounted will be minimized; to provide improved driving mechanism for a feed-belt on one of the movable members of the projector support; to improve the construction and operation of the machine set forth in Letters Patent No. 1,309,833, dated July 15, 1919, and No. 1,335,642, dated March 30, 1920; and to provide an improved manner of mounting and balancing the pivot-member of the machine which support the motor and the sand projector.

The invention consists in the several novel features hereinafter set forth and more particularly defined by claims at the conclusion hereof.

In the drawings: Fig. 1 is a side elevation of a machine embodying the invention. Fig. 2 is a vertical transverse section through the gearing for driving the belt for delivering sand to the projector. Fig. 3 is an axial section through the pivoted supporting arm. Fig. 4 is an end elevation of the mechanism for vibrating the combined conveyor and riddle, the case being shown in section. Fig. 5 is a section through the projector. Fig. 6 is a detail of the gearing for driving the belt for conveying sand to the projector.

The invention is exemplified in a machine mounted on a base 10 on which is pivotally mounted to swing laterally a jib 11 which comprises a socket 12 suitably journalled on the standard 10, a tube 13 and a bearing-socket 14 at its outer end in which is pivotally mounted a stud 17 on a horizon-

tally movable arm which supports the sand-projector. This arm comprises a casing 15 secured by bolts 16 to a flange on the top of stud 17 which permits the arm to swing laterally relatively to the jib and a tube 18 which has its inner end secured in the casing 15 and supports the projector at its outer end.

The projector comprises a head 20 on which is secured a projector blade 21 with a cut-off blade 22 at one side and a casing 23, having an arcuate periphery which cooperates with the blade 21 in projecting the sand into a flask beneath the projector. A yoke 24 secured on the tube 18 supports the casing 23 in fixed relation theron. Screws 25 secure the casing to the yoke.

An electric motor 26 is bolted to one end of the casing 15 and the shaft 27 of said motor extends through casing 15 and tube 18 and projects beyond the outer end of said tube. Roller bearings 28 and 29 are mounted on the outer portion 30 of the tube 18, and these bearings are within the head 20 of the rotor and radially aligned with the impeller blade 21, so that they will directly support the rotor on the tube 18 within that portion of the rotor which is disposed within the plane of rotation of the blade. Nuts 31 hold the stationary member of the roller bearing 28 on the tube 18. To provide a driving connection between the shaft 27 and the rotor-head, the shaft 27 is extended, as at 27', beyond the outer end of the tube 18 and a driving collar or member 33 is secured to the outer end of said shaft by a key 34. Bolts 36 extend through the marginal portion of the collar and into the hub of head 20, to secure the collar to the projector head so that the latter will be driven from the shaft 27. A plate 38, provided with packing rings 39, is bolted to the rotor-head 20 to retain the lubricant for the bearings 27 and 28 in the space between the head and the tube or sleeve 18. This construction exemplifies one, in which anti-friction bearings are interposed directly between the tubular arm and the hub of the rotor, disposed radially inward of the impeller blade, so that the rotor will have a direct support within the plane of rotation of the impeller. This construction, in practice, has been found to minimize the vibration of the arm and the rotor, resulting from the high speed operation of the latter. By eliminating this vibration, ex-

cessive wear upon the parts affected thereby is eliminated.

The purpose in providing an arm and a jib to support the projector-head is to permit it to be moved horizontally to pack all portions of a flask. The mechanism for feeding sand to the projector-head comprises an inclined chute 40, which contains a riddle 60 and supported over the jib 11, and an endless belt 41 supported over and movable with the supporting arm. The chute 40 delivers the sand to a guide 42 which is supported by the supporting arm and guides the sand onto the belt 41. The latter delivers the sand through an open side 43 into the casing 23, to the rotor of the projector. In practice, considerable difficulty has been experienced in the operation of these feeding devices from the vibration caused by the vibratory conveyor and riddle. For the purpose of minimizing this vibration, one end of the conveyor 40 is pivoted by a bolt 44 to the upper end of a lever 45 which is fulcrumed, at 46, in brackets 47 secured to the base of a bracket 48 which is secured to the top of the sleeve 12 of the arm 11. An enclosing case 48' for this gearing is secured to the top of the bracket 48. The other end of the chute is supported from the arm 11 by a resilient strip 49. A counterweight 50 depends from the fulcrum of the lever 45 and is disposed so that its force will be applied to hold the lever 45 in a vertical position and the chute 40 in a medial position between the extremes of its movement. In this manner, the resistance of the weight 50 is applied to cumulatively increase as the chute swings to either side of its medial position and so as to retard the chute as it approaches the extremes of its movement. An arm 51 is formed on the lever 45 so that the latter will operate as a bell-crank. A link 52 connects the outer end of arm 51 and a wrist-pin 53 on a gear 54 which is mounted on a shaft 55 held in a bearing 56 which is secured to the bracket 48. An electric-motor 57 is bolted to bearing 56 and its shaft is provided with a pinion 58 which meshes with gear 54 to operate the wrist-pin 53 to oscillate lever 51, 45, weight 50 and to vibrate the chute. A counterweight 54' on gear 54 counterbalances the link 52 and its connections. Link 52 and arm 51 form a connection by which the wrist-pin 53 operates the chute 40, so that the wrist-pin will cross its dead-center points while the chute is moving near the ends of its stroke. This construction has been found to be an important factor in eliminating most of the vibration of the supports caused by the vibratory chute. The inner or upper end of chute 40 is adapted to receive sand from a stationary chute or elevator, as well understood in the art, and a riddle 60 separates the fragments of castings or other material from the sand. This mechanism for

operating the vibratory conveyor-chute exemplifies a construction which will minimize the vibration of the supporting structure upon which the chute is carried.

The mechanism for driving the conveyor-belt 41, which delivers sand from the chute 40 to the projector-casing, comprises a bevelled pinion 61 which is keyed to the shaft 27 in the casing 15; a bevelled gear-wheel 62, meshing with pinion 61 and fixed to a transverse shaft 63, which is mounted in roller bearings 64 and 65; a pinion 66 fixed to shaft 63, an idler-gear 67 on a stud-shaft 68 and meshing with pinion 66; and a gear 69 fixed to the hub 70 of a pulley 71, around which the belt 41 passes, and by which it is driven. A stationary shaft 72 extends through the pulley 71 and anti-friction rollers 73 rotatably support pulley 71 from said shaft. One of the bearings 73 is mounted in a removable end 74 of the pulley 71 and packing 75 is provided in said pulley-end to prevent the escape of lubricant from the chamber in the pulley. A bracket 76, secured to the casing 15 by bolts 77, supports one end of the shaft 72. Bearings 64 and 65 for shaft 63, stud-shaft 68, the other end of shaft 72 are mounted in a gear-casing comprising an inner section 78 which is formed and secured to close one open side of the casing 15 and a cover-section 79 which is secured to section 78 by bolts 80. A cap 81 is secured to cover-section 79 by bolts 82 and is removable to provide access to an adjusting nut 83 for the bearings for the shaft 63. The hub 70 of pulley 71 extends through case-section 78 and packing rings 84 prevent leakage of lubricant between said section and said hub. Casing 15 is adapted to contain oil to lubricate the gearing and opening 86 is formed in the case-section 78 so the oil will flow into the gear-case 78, 79. An oil splasher 85 is formed on the pinion 66 to splash oil into the upper portion of said gear-case so that all of the gearing in the case will be lubricated. A space is formed between the hub 70 and the shaft 72, so that some of the oil splashed into the upper portion of the case will find its way into the pulley 71 to lubricate the bearings 73. Packings 75 and 84 prevent the escape of oil from the gearing. A space 18^a is provided between the shaft 27 and tube 18 through which oil will be splashed and fed to the bearings between the rotor and said tube.

The invention exemplifies gearing between the motor driven shaft 27 and the conveyor-belt which is enclosed and lubricated and by which the bearings at the outer end of the shaft will be lubricated. As a result, this gearing will not be exposed to particles of sand escaping from conveyors and will wear a long time.

The outer end of the belt 41 is guided by an idler pulley 87 which is rotatably mount-

ed in suitable manner on a shaft 88 which is secured in bearings 89 on the yoke 24.

In the construction illustrated and described, the pivot 17 for the jib is disposed between the motor 26 and the projector head, in lieu of disposing the pivot directly beneath the motor. As a result of this relative disposition of the projector-head, motor and jib-pivot, the motor will be disposed to counterbalance the projector head and this arrangement measurably avoids excessive friction at the pivotal support for the jib, so that it may be freely shifted as desired by the operator and aids in eliminating vibration.

15 The invention is not to be understood as restricted to the details set forth, since these may be modified within the scope of the appended claims, without departing from the spirit and scope of the invention.

20 Having thus described the invention, what we claim as new and desire to secure by Letters Patent, is:

1. In a molding machine, the combination of a support, a projector comprising a stator 25 sustained by said support and a rotor having a projector blade rigidly secured thereon, a bearing for the rotor disposed inwardly of the zone of rotation of the blade, and a driving connection for the rotor.

30 2. In a molding machine, the combination of a support, a projector comprising a stator sustained by said support and a rotor having a blade rigidly secured thereon for projecting sand from the stator, a shaft for the 35 rotor, a bearing disposed inwardly of the zone of rotation of the blade on the rotor, and a driving connection between the rotor and said shaft.

3. In a molding machine, the combination 40 of a tubular support, a projector comprising a stator carried by said support and a rotor for projecting sand from the stator, a shaft in said tubular support, a bearing disposed inwardly of the zone of rotation of the blade 45 on the rotor and between the rotor and the tubular support, and a driving connection between the rotor and said shaft.

4. In a molding machine, the combination 50 of a tubular support, a projector comprising a stator carried by said support and a rotor having a blade for projecting sand from the stator, a shaft in said tubular support, the latter extending axially through the rotor, a bearing within the rotor and between the 55 rotor and the tubular support whereby the rotor will be directly supported by said bearing, and a driving connection between the shaft and the rotor.

5. In a molding machine, the combination 60 of a tubular support, a projector comprising a stator carried by said support and a rotor having a blade for projecting sand from the stator, a shaft in said tubular support, the latter extending axially through the rotor, 65 a bearing within the rotor and between the

rotor and the tubular support whereby the rotor will be directly supported by said bearing, the shaft extending beyond the end of the tubular support, and a driving connection between the projecting end of the shaft 70 and the rotor.

6. In a molding machine, the combination of a tubular support, a projector comprising a stator carried by said support and a rotor having a blade for projecting sand from the 75 stator, a shaft in said tubular support, the latter extending axially through the rotor, an anti-friction bearing between the rotor and the tubular support, whereby the rotor will be directly supported by said bearing, 80 the shaft extending beyond the end of the tubular support, and a driving connection between the projecting end of the shaft and the rotor.

7. The combination of a molding machine, 85 means for conveying sand to said machine comprising a vibratory chute, mechanism for operating said chute comprising a pivoted lever and counterbalancing means applied to the lever.

8. The combination of a molding machine, means for conveying sand to said machine comprising a vibratory chute, mechanism for operating said chute comprising a pivoted lever and a counterweight applied to the 95 lever to move oppositely to said chute.

9. The combination of a molding machine, means for conveying sand to said machine comprising a vibratory chute, mechanism for operating said chute comprising a pivoted lever and counterbalancing means for the 100 chute rigid with the lever.

10. In a molding machine, the combination of a support, means carried by said support for discharging sand into a flask, 105 means carried by said support for conveying sand to said discharge means comprising a vibratory chute, mechanism for operating said chute comprising a pivoted lever, and counterbalancing means for the chute.

11. In a molding machine, the combination of a support, means carried by said support for discharging sand into a flask, means also carried by said support for conveying sand to said discharge means comprising a vibratory chute, mechanism for operating said chute comprising a pivoted lever and an eccentric connected to the lever, and counterbalancing means for said eccentric connection.

12. In a molding machine, the combination of a support, means carried by said support for discharging sand into a flask, means carried by said support for conveying sand to said discharge means comprising a vibratory chute, mechanism for operating said chute comprising a pivoted lever and an eccentric connected to the lever, and a counterweight on the lever.

13. The combination of a molding ma- 130

chine, means for conveying sand to said machine comprising a vibratory chute, and mechanism for operating said chute comprising a bell-crank lever connected to the chute, a link connected to said lever, a wrist-pin connected to the link and mechanism for operating said wrist-pin.

14. The combination of a molding machine, means for conveying sand to said machine comprising a vibratory chute, mechanism for operating said chute comprising a bell-crank lever pivoted to the chute, a link connected to said lever, a wrist-pin connected to the link and mechanism for operating said wrist-pin, and counterbalancing means applied to the lever.

15. In a molding machine, the combination of a support, means carried by said support for discharging sand into a flask, means also carried by said support for conveying sand to said discharge means comprising a vibratory chute, and mechanism for operating said chute comprising a bell-crank lever, a link connected to said lever, a wrist-pin connected to the link and mechanism for operating said wrist-pin and a counterweight rigid with the lever.

16. In a molding machine, the combination of a projector, a movable support for the projector, an endless belt to feed sand to the projector mounted on and movable with the support, a motor for driving the rotor mounted on the support, gearing between the motor and the belt, and means for enclosing said gearing.

17. In a molding machine, the combination of a projector, a movable support for the projector, an endless belt to feed sand to the projector mounted to move with the support, a motor for driving the rotor mounted on the support, gearing between the motor and the belt, and a case for enclosing said gearing and provided with means to lubricate the gearing from said case.

18. In a molding machine, the combination of a projector, a movable support for the projector, an endless belt to feed sand to the projector mounted on and movable with said support, a motor for driving the rotor mounted on the support, spur-gearing between the motor and the belt, and means for enclosing said gearing.

19. In a molding machine, the combination of a projector, a movable support for the projector, an endless belt to feed sand to the projector mounted on and movable with the support, a motor for driving the rotor mounted on the support, a common shaft for the motor and the rotor of the projector, and mechanism for driving the belt from said shaft comprising a pinion on said shaft and spur gearing driven by said pinion.

20. In a molding machine, the combina-

tion of a projector, a movable support for the projector, an endless belt to feed sand to the projector mounted on and movable with said support, a motor for driving the rotor mounted on the support, a common shaft for the motor and the rotor of the projector, mechanism for driving the belt from said shaft comprising a pinion on said shaft and spur gearing driven by said pinion and a case enclosing said gearing.

21. In a molding machine, the combination of a movable support, a motor on said support, a projector comprising a rotor mounted on the support, a shaft between the projector and the motor, an endless belt mounted for delivering sand to the projector movable with the support, pulleys for the belt mounted on the support, gearing between the shaft and one of the pulleys for driving the belt, and a casing enclosing said gearing and provided with means to lubricate said gearing.

22. In a molding machine, the combination of a movable support, a motor on said support, a projector comprising a rotor mounted on the support, a shaft between the projector and the motor, an endless belt mounted for delivering sand to the projector movable with the support, pulleys for the belt mounted on the support, gearing between the shaft and one of the pulleys for driving the belt, and a casing enclosing said gearing and provided with means to lubricate said gearing and one of said pulleys.

23. In a molding machine, the combination of a movable support, a motor on said support, a projector comprising a rotor mounted on the support, a shaft between the projector and the motor, an endless belt for delivering sand to the projector, pulleys for the belt mounted on the support, gearing between the shaft and one of the pulleys for driving the belt, and a casing adapted to contain lubricant and enclosing said gearing.

24. In a molding machine, the combination of a movable support, a motor on said support, a projector comprising a rotor mounted on the support, a shaft between the projector and the motor, an endless belt for delivering sand to the projector, pulleys for the belt mounted on the support, gearing between the shaft and one of the pulleys for driving the belt, and a casing adapted to contain lubricant and enclosing said gearing, and bearings for the driven pulley connected to receive lubricant from said casing.

25. In a molding machine, the combination of a tubular support, a motor on said support, a projector comprising a rotor mounted on the support, a shaft in said support between the projector and the motor, means for delivering sand to the projector, gearing driven by the shaft for operating said delivery means, and a casing adapted

to contain lubricant and enclosing said gearing, and a bearing for said shaft connected to receive lubricant from the casing.

26. In a molding machine, the combination of a movable tubular support, a motor on said support, a projector comprising a rotor mounted on the outer end of the support, means for delivering sand to the projector, gearing between the shaft and one of the pulleys for operating said means, a casing adapted to contain lubricant and enclosing said gearing, and a bearing for the rotor connected to the casing so as to receive lubricant therefrom.

15 27. In a molding machine, the combination of a support, a motor mounted at one end of the support, a sand projector driven by the motor mounted at the other end of the support, a pivot for said support disposed 20 between the motor and the projector so that the motor will counterbalance the projector.

28. In a molding machine, the combination of a support, a motor mounted at one end of the support, a sand projector driven 25 by the motor mounted at the other end of the support, delivery means mounted on said support, gearing driven by the motor for

driving said means, a pivot for said support disposed between the motor and the projector so that the motor will counterbalance 30 the projector.

29. In a molding machine, the combination of a tubular support, a projector mounted on one end of the support, a motor mounted at the other end of the support, a 35 shaft between the motor and the projector extending through the tubular support, and a pivot for the support disposed between the motor and the projector so that the motor will counterbalance the projector. 40

30. In a molding machine, the combination of a tubular support, a projector mounted on one end of the support, a motor mounted at the other end of the support, a shaft between the motor and the projector 45 extending through the tubular support, means mounted on and movable with the support for delivering sand to the projector, gearing for operating said means from said shaft, and a pivot for the support disposed 50 between the motor and the projector so that the motor will counterbalance the projector.
